[57] CLAIM

The ornamental design for a multi-port hopper exhaust apparatus, as shown and described.

DESCRIPTION

FIG. 1 is a top perspective view of a multi-port hopper exhaust apparatus showing our new design; FIG. 2 is a rear elevational view thereof; FIG. 3 is a left side elevational view thereof; FIG. 4 is a right side elevational view thereof; FIG. 5 is a front elevational view thereof; FIG. 6 is a top plan view thereof; and, FIG. 7 is a bottom plan view thereof.

The broken line showing of the lawnmower in FIG. 1 is for illustrative purposes only, and forms no part of the claimed design.
